UNITED STATES PATENT OFFICE.

ERNEST O. CARTWRIGHT, OF SPRINGFIELD, OHIO, ASSIGNOR OF ONE-THIRD TO LOUIS K. FISHER, OF DAYTON, OHIO, AND ONE-THIRD TO BYRON D. CAMPBELL, OF WEST MILTON, OHIO.

PILE-ELEVATOR FOR SHEET-FEEDING MACHINES.

1,141,773.

Specification of Letters Patent.

Patented June 1, 1915.

Application filed February 10, 1913. Serial No. 747,379.

To all whom it may concern:

Be it known that I, ERNEST O. CARTWRIGHT, residing at Springfield, in the county of Clark and State of Ohio, have invented a new and Improved Pile-Elevator for Sheet-Feeding Machines, of which the following is a specification.

My present invention, which in its general nature has reference to printing machines, and particularly to printing presses having means for automatically feeding the sheet to the printing cylinder, and while under ordinary adjustments of its parts, may be readily combined and arranged to 15 coöperate with any of the automatic sheet feeding mechanisms in general use, it is more particularly designed for forming a coöperative part of, and particularly adapted for serving as a part of the complete 20 construction of my rotary cylinder high speed job printing press disclosed in my co-pending application Serial No. 747,375 filed on even date with this application.

The primary object of my present invention is to provide a means for automatically elevating a pile of sheets, that is simple in construction, can be encompassed in relatively small space, and which will effectively serve for its intended purposes.

Another object of my invention is to provide a simple, compact and easily adjusted mechanism in which the operation of elevating the pile is automatically controlled by the height of the pile of sheets in the 35 elevator itself as the said pile of sheets is constantly reduced.

With other objects in view that will hereinafter appear my present invention comprehends the pile elevating means for sheet 40 feeding machines that embodies the peculiar construction and arrangement of parts hereinafter fully explained, specifically pointed out in the appended claims and illustrated in the accompanying drawings, in 45 which:

Figure 1 is a central vertical section of my sheet pile elevating mechanism, so much of the rear end of my complete printing press shown in my copending application 50 before referred to, being illustrated as is necessary to disclose a practical arrangement of my present invention. Fig. 2 is a side elevation thereof looking at the machine in a direction opposite to Fig. 1. Figs.

3 and 4 are diagrammatic views, illustrating two steps in the paper pile elevating operation or movement. Fig. 5 is a detail vertical section thereof taken on the line 5-5 on Fig. 3. Fig. 6 is a detail cross section on the line 6-6 on Fig. 5, and particularly showing the pawl and ratchet devices by which the piled sheets is elevated. Fig. 7 is a detail perspective view of the eccentric device on one end of a main shaft hereinafter referred to. Fig. 8 is a detail view of the pendent, hereinafter described. Fig. 9 is a detail perspective view of the pawl that coöperates with the pendent member and the ratchet wheel hereinafter further referred to. Fig. 10 is a detail perspective view of the "calipering frame", the positioning of which, relatively to the paper pile being elevated, governs the progressive vertical feed of the elevator and the paper pile.

Referring now more particularly to Figs. 1 and 2 of the drawings, 1 designates a driven shaft that is actuated by a main driving shaft suitably located at the feed end of the printing press frame. Adjacent the shaft 1, and located somewhat below the normal top of the pile of sheets, is another shaft, 3, and the said shaft is disposed parallel with the shaft 1. On the shaft 3, at the opposite sides of the supporting frame, are fixedly held sprockets 4, of the smallest practical diameter and at a point beyond the frame and near one end the said shaft 3 carries a toothed ratchet wheel 5. 6 designates a reciprocating pawl carrying arm, one end 90 of which is revolvably mounted on shaft 3 and the other end of which is provided with a connection for receiving one end of an eccentric strap 7, the other end of which is suitably mounted on the eccentric 2 of the 95 device 8. Ratchet wheel shaft 3 also carries a crank 9 for hand operation. 10 designates a pawl shown in detail in Fig. 9, that is mounted on the arm 6 for engaging the ratchet wheel 5, and it is normally held out 100 of engagement with the said ratchet wheel by a spring 11, of just sufficient tension to hold the said pawl out of operative engagement with the said ratchet 5. 12 designates a hand released holdback pawl for engaging the ratchet wheel 5. At a convenient point on each side frame, is a stud 13 from which is suspended a pair of guides or strips

14, which form vertical guideways for the trunnions on the ends of the elevator, that is mounted between the said guides as shown. The studs 13 also afford fastenings 5 for one end of the sprocket chains 15 whose free ends pass over the sprockets 4, at their respective sides, and with their loose ends hung from the said sprockets 4 unfastened.

The method of mounting the sprocket 10 chains in the manner stated and shown affords the effect of gearing to diminish the amount of lift the elevator would receive from a full tooth movement of the ratchet wheel 5, if the chains were connected direct 15 to the elevator 23 and also admits of a smaller diameter in the ratchet wheel to afford the desired number of teeth.

At a point somewhat above the desired top of the pile of sheets, and at a convenient 20 distance rearwardly of the forward edge of the pile, is a frame 16, of light construction and it is hinged on both sides of the frame of the machine. The frame 16 is extended forwardly to a point where one 25 side thereof may be conveniently operated upon by a timing device, actuated from a driving part of the power mechanism. The timing device, best shown in Figs. 3 and 4 of the drawings, includes a cam 24 that is 30 mounted on the main driving shaft 24^a and it supports the forward end of the hinged frame 16, the face of the said cam 24 being designed for permitting the said frame 16 to drop at predetermined times. The front 35 end of the hinged frame 16 is lifted, at predetermined times, by a lever-like extension 17 that is connected with an arm which includes a pendent portion that carries a drop roller 17^a that engages and is supported by 40 the cam 24 on the main driving shaft as shown. On that side of the hinged frame 16, and immediately above the ratchet wheel 5, is pivotally mounted a gravity lever 19 whose lower end is bifurcated to straddle 45 the ratchet wheel shaft 3 and thereby be anchored against pendulous motion, and the said lever 19 is positioned between the machine frame and the ratchet wheel 5. Gravity lever 19 includes an arc shaped abutment 50 20 having the radius of the ratchet wheel 5 and the said abutment extends approximately the full width of the ratchet wheel 5, it being of such length to practically house or cover the entire movement of the pawl 10. 55 21 designates a caliper rod and the said rod is pivotally suspended from a hinged frame 16 that includes a pair of transverse members 16^a—16^b. The rod 21 is mounted to follow the movement of the frame 16 and it extends the full width of said frame in order to be always in position for any size of sheets without regard to the position of the pile on the elevator.

60 For correct operation of the elevator, the power from which my elevator mechanism

is served, for example the power shaft of my printing press, before referred to, is so set and so operated that the movement of the hinged frame 16 is such that that arm that carries the pawl 10 is operated the movement the hinged frame 16 is "down".

The operation of my automatically operating pile elevating means, is briefly explained as follows: A pile of sheets is placed on the elevator shelf 23, and the latter, with 75 the sheets, is lifted by the hand crank 9 on the ratchet wheel shaft 3, to bring the top of the sheet pile to the desired height, it being understood the hand released pawl 12 holds the ratchet against back rotation and supports the elevator. The caliper rod 21 is set by means of its adjustable connection 22 to a position that allows the hinged frame 16 to suspend the gravity lever 19 at a point where the pawl 10 is just out of engagement 80 with the ratchet wheel 5 while the caliper- 85 ing rod or bar 21 rests upon the normal top of the pile of sheets and supports the hinged frame 16 while it is at its "down" position. Upon the operation of the power shaft 1, to 90 which motion has been transmitted, from the power shaft of the press as shown in my copending application before mentioned, the pawl 10 makes its full movement out of engagement with the teeth of the ratchet wheel, 95 and it repeats that performance at each impulse of printing operation of the machine with which my elevating means is combined, until a sufficient number of sheets have been removed from the top of the pile to allow 100 the caliper rod to lower far enough to permit the gravity lever 19, through its arc portion or abutment 20 to press the pawl 10, 105 down into engagement with the ratchet wheel 5 so that the said pawl 10, on its next drawing impulse, pulls the ratchet wheel over one or more teeth, as the adjustments may be, to restore the position of top of the pile.

By moving the controlling eccentric 2, (that is held on the shaft 1 by a set screw 8), with relation to the timing device of the hinged frame 16, a greater or less duration of contact of the pawl 10 with the ratchet wheel may be taken advantage of, and the amount of lift of the elevator at each impulse, be governed for different thickness of material being fed.

The foregoing described operation is illustrated in Figs. 3 and 4 by reference to which it will be noticed that the normal top surface level of the pile of sheets on elevator 23 has dropped; the caliper rod 21, by reason of its connection with the member 17 and the roller 17^a that engages the timing cam 24 are down and resting on the top of the pile which being below normal, as hereinbefore mentioned, has permitted the pendent 19 to fall far enough so that its arcuate portion 20 has pressed the pawl 10 into engagement 110 115 120 125 130

with the ratchet wheel 5. Now as the eccentric 2 rotates in the direction of the arrow, arm 6 is forced downwardly, carrying pawl 10 with it until the parts assume the 5 position indicated in dot and dash lines in Fig. 4 from which it will be seen that the above-mentioned parts have moved the ratchet wheel 5 over, the distance of one tooth (compare lines 25 on Figs. 3 and 4) 10 thereby rotating sprockets 4 and raising elevator 23 so that the paper assumes its normal top level. When this movement has been completed cam 24 will have reached the position indicated in Fig. 4, at which time 15 it will raise the arm carrying finger 17 and consequently frame 16 will be carried upwardly so as to disengage the caliper rod 21 and free the top of the sheet pile. At this time the parts assume the full lever 20 position in Fig. 4, pawl 10 is freed from engagement with the ratchet 5, the further movement of eccentric 2 being of no avail for elevating the paper pile, it will readily be seen however, (as has been previously 25 mentioned) that should the eccentric 2 be set back far enough so that it may get the advantage of its entire sweep before the cam 24 raises the frame 16 and consequently rod 19, the ratchet 5 will be rotated through a 30 greater arc and the elevator 23 be subject to a greater degree of lift.

To lower the pile elevator, for renewal of the pile or other reasons, the same is readily effected by suspension of the pawls and the 35 use of the hand crank on the ratchet wheel shaft. From the foregoing taken in connection with the accompanying drawing, the advantages of my sheet pile elevating mechanism and its complete structure thereof, it 40 is believed will be readily apparent to those skilled in the art to which the invention relates.

What I claim is:

1. A pile elevator for sheet feeding machines comprising in combination with means for feeding off the topmost sheet or sheets at predetermined times; means for lifting the sheet pile to a normal level, operative mechanism therefor operative upon the 45 removal of a top sheet or sheets for setting the lifting means into action, the said mechanism including a driving ratchet, a pawl, a pawl carrying member, an adjustable device for moving the pawl and having provision 50 for timing the stroke of the pawl, means continuously tending to disengage the pawl from the ratchet, and a reciprocably mounted member held in loose contact with the pawl and coöperating with the sheet pile 55 for moving the pawl into engagement with the ratchet.

2. In a pile elevating mechanism for sheet feeding machines in which is included means for feeding off the topmost sheet or sheets 60 at predetermined times; means for lifting

the sheet pile to a normal level, actuating mechanism therefor operative upon the removal of a top sheet or sheets from the sheet pile for setting the lifting means into action, the said mechanism including a driving ratchet, a pawl, and a swinging carrying member on which the pawl is supported, means for adjusting the carrying member to thereby determine the time of swing of the said member and the consequent effective 70 stroke of the pawl, means for normally forcing the pawl out of engagement with the ratchet and other means that coöperates with the sheet pile for engaging the pawl after it has completed its thrust or ratchet 75 stroke to cause the pawl to engage the ratchet.

3. A sheet pile elevator for sheet feeding machines that comprises in combination with means for feeding off the topmost sheet 80 or sheets from the pile; means for automatically raising the elevator to bring the top of the sheet pile to a normal plane with respect to the sheet feeding means, the said elevator raising means including a step-by-step ratchet wheel controlled lift, an eccentric controlled arm, a pawl carried thereby that is normally held out of engagement with the ratchet wheel, means for moving the pawl into operative engagement with the 85 said ratchet wheel, the said means being set into operation when the top of the sheet pile drops to a predetermined degree from the normal level, and means for timing the throw of the eccentric controlled arm that carries 90 the pawl and the consequent rotation of the ratchet wheel and the lift movement of the pile elevator governed by the movement of the 95 said ratchet.

4. A sheet pile elevator for sheet feeding 100 machines, that comprises in combination with a means for feeding off the topmost sheet or sheets from the pile, at predetermined intervals; a means for automatically raising the elevator to bring the top of the 105 sheet pile to a normal plane with respect to the sheet feeding means, said elevator raising means including a step-by-step ratchet wheel controlled lift, an eccentric controlled arm and a pawl carried thereby that is normally held out of engagement with the ratchet, and a means for moving the said 110 pawl into operative engagement with the ratchet wheel, said means being set into operation when the top of the sheet pile drops 115 to a predetermined degree from the normal level, the eccentric that controls the pawl carrying arm being adjustably mounted with respect to the ratchet wheel whereby to time the throw of the pawl and the consequent rotation of the ratchet and the lift 120 movement of the pile elevator.

5. A sheet pile elevator for sheet feeding 125 means; that comprises in combination with means for feeding off the topmost sheet or 130

sheets from the pile at predetermined intervals, a means for automatically raising the elevator to bring the top of the sheet pile to a normal plane with respect to the sheet feeding means, the said elevator raising means including a step-by-step ratchet wheel controlled lift, an eccentric controlled arm and a pawl carried thereby that normally tends to move out of engagement with the ratchet wheel, the said means being set into operation when the top of the sheet pile drops to a predetermined degree from the normal level, said means including a caliper rod for engaging the top of the sheet and a connection that coacts with the said rod and with the ratchet engaging pawl and adapted for forcing the said pawl into engagement with the said ratchet wheel as the caliper rod falls, and an eccentric that controls the pawl carrying arm, the said eccentric being adjustably mounted upon one of the driven shafts of the machine.

6. In a sheet pile elevator for sheet feeding means, the combination with mechanism that intermittently feeds the topmost sheet or sheets off the pile; of a means for elevating the sheet pile to a normal top level, the said means consisting of a vertically swingable frame, said frame including a pair of

transverse members 16^a, 16^b, a caliper rod 30 pendently supported from the transverse member 16^b for engaging the top of the sheet pile and tending to normally hold the frame to its minimum height, a step-by-step advancing mechanism for lifting the sheet pile 35 to its normal level, said mechanism including a ratchet wheel, an eccentric controlled arm and a pawl carried thereby for engaging said ratchet wheel, said pawl being normally held under spring tension away from the ratchet wheel, a member that normally engages the pawl for forcing it into engagement with the said ratchet wheel, said member being pendently supported from one of the cross members of the vertically swingable frame, and a lifting lever that engages the underside of the transverse member 16^a of the swingable frame, and a timing mechanism that coöperates with and lifts the lever at predetermined times whereby to lift 45 the member that holds the pawl in engagement with the ratchet wheel to allow the said pawl to become disengaged from the said wheel.

ERNEST O. CARTWRIGHT.
